UNITED STATES PATENT OFFICE.

PETER JOHN BERTELSEN AND GEORGE KEENAN, JR., OF SAN FRANCISCO, CALIFORNIA.

DESIGN FOR A FOUNTAIN-BRUSH.

47,098.

Specification for Design.

Patented Mar. 16, 1915.

Application filed October 3, 1914. Serial No. 864,955. Term of patent 7 years.

To all whom it may concern:

Be it known that we, PETER J. BERTELSEN and GEORGE KEENAN, Jr., citizens of the United States, residing at San Francisco, in the county of San Francisco and State of California, have invented a new, original, and ornamental Design for Fountain-Brushes, of which the following is a specification, reference being had to the accompanying drawing, forming part thereof.

The figure is a perspective view of the fountain brush, showing our new design.

We claim:—

The ornamental design for a fountain brush, as shown.

PETER JOHN BERTELSEN.
GEORGE KEENAN, Jr.
